MARINE STRUCTURE

George H. Atkinson, Mason City, Wash.

Refiled for (abandoned) application Serial No. 739,023, August 8, 1934. This application September 3, 1936, Serial No. 99,323

4 Claims. (Cl. 61—34)

My present invention relates generally to filled, partially filled or unfilled coffer dams, piers, quay walls, marginals, wharves, breakwaters, subways and other marine structures, and has for its primary object the improvement thereof in respect not only to strength, effectiveness and durability in use, but also in respect to its fabrication in the first instance and its subsequent removal, where desirable or necessary.

Generally speaking my invention contemplates the fabrication of spaced walls of sheet piling in connection with the ends of transversely disposed and spaced apart cross frames so constructed that they may be pre-formed, transported to the site of installation, lowered to the desired position, secured in this position by individual anchoring piles, and each serve as a temporary support while the next adjacent frame is being anchored, and it is a further object to provide a construction which will permit the various parts to be readily salvaged by reversing the above order in the removal of the structure.

Further and more specific objects of my invention, relating to the construction, arrangement and cooperation of the several parts thereof, facilitating fabrication and erection, will be better understood and more thoroughly appreciated from the following detailed description, reference being had to the accompanying drawings, which form a part of this specification, and in which,

Figure 1 is an upstream elevation of a coffer dam under construction according to the provisions of my invention.

Figure 2 is a top plan view of a portion thereof. Figure 3 is a vertical, transverse section therethrough, taken substantially on line 3—3 of Figure 2.

Figure 4 is a vertical, longitudinal section therethrough, taken substantially on line 4—4 of Figure 2.

Figure 5 is an enlarged detail of the parts included within the broken line A—A of Figure 2, partly in top plan and partly in horizontal section.

Figure 6 is an enlarged detail perspective view illustrating the connections between each cross frame and one of its anchoring piles, and,

Figure 7 is a similar view to Figure 5, showing a slightly modified structure.

Referring now particularly to Figure 1, and as in my abandoned application Serial Number 739,023, filed August 8, 1934, of which this application is a substitute, I have shown, in a more or less diagrammatic manner, installation in connection with a partially erected marine structure

wherein a series of individually anchored cross frames 10 serve to support sheet piling 11 fabricated in connection with the ends of the frames 10 in a manner which will presently be plain, and driven into the river or other bed 12 to the desired depth.

The several frames 10, each including side cross members having vertical pile guides 13 of suitable form, are pre-formed, or assembled at a convenient point and transported to the site of installation by a barge 14, or other suitable means, as I have shown in connection with a frame 10a in Figure 1. Frame 10a is then picked up by suitable means, either on the partially completed structure or on the barge or other vessel, and held in the desired manner and in vertical position as frame 10b is shown in Figure 1, parallel with, and spaced from, the last previously anchored frame 10, which has been secured in position by driving anchoring piles 15 into the bed 12 through the guides 13.

Each frame, thus moved from position 10a to position 10b, is temporarily locked to the adjacent anchored frame 10 by a spacing frame 16, until its anchoring piles 15 have been driven into the bed 12, after which spacing frame 16 may be removed for use in similarly holding the next frame lowered in the line of installation. Each frame in turn is either allowed to rest on the bed 12 or attached to its anchoring piles 15 in a manner to be presently described, and is then released from the handling equipment, and to serve its stated purpose the spacing frame 16 consists of cross struts 23 suitably braced and connected, by diagonals 24, to vertical side bars 25 having a sliding, interlocking connection with companion bars 26 laterally outstanding from the outer sides of the frames 10. These interlocking connections may be of the head and claw type shown, and it will be understood that the spacing frame 16, as a whole, will be of sufficient strength and length to accomplish its intended function.

After the frames have been thus anchored, a working platform 1 may be constructed on the anchoring piles 15, and the interlocking sheet piling 11 is then driven into the bed 12, along arcuate lines across and between the ends of the frames 10, so as to present outwardly convex surfaces and transmit the pressure to the frames 10 in line with the anchoring piles 15. It is obvious unwatering of the structure can be done from within the two spaced apart walls of sheet piling 11, the individual piles of which are interlocked with one another as by means of head and

claw connections, or a fill may be made between the walls and an area encircled by the structure may be unwatered.

- With the above in mind, it will be more readily understood by reference to Figures 2 to 6 inclusive that each of the supporting frames 10 has two side portions or cross members, and that each of these cross members consists of a series of pile guides in the nature of upright beams 17 arranged in spaced apart relation in pairs between, and connected at vertically spaced points to, spaced apart horizontal beams 18, whereby the spaces between the beams 17 of each pair serve as effective vertical guides for the anchoring piles 15.
- 15 Certain of the vertical beams 17 are at the outer ends of the cross members of each frame, and to these beams are secured endwise outstanding, interlocking bars 20 and laterally outstanding, interlocking bars 22. It will be seen 20 that the cross members of each frame 10 are, furthermore, suitably connected and braced by cross beams 18a, and diagonals in the form of rods, bars and the like 19.

As shown particularly in Figure 5, the arcuate sections of the sheet piling walls are joined to the frame ends by special, substantially H-shaped sheet piling members 45, whose outer interlocking extensions connect with the wall sections and whose inner, interlocking extensions similarly 30 connect with the endwise outstanding bars 20 of the frames. All of these connections may be of the head and claw type, although as shown in Figure 7, the special sheet piling connecting members may have the triangular form seen at 45a, 35 thus presenting a single inner extension for connection with a single head and claw bar 20a fixed to the outermost upright of each frame side member. In either form of connection, it is obvious the outer end uprights 17 of the frames must be 40 of sufficient strength to transmit the loads from the sheet piling walls to the frames 10, and may for this purpose be reenforced by bracing 27, if necessary.

As also shown in Figure 7, the anchoring pile guides may be formed by utilizing cylindrical uprights 17a in the frames, and it is to be understood that instead of using complete frames 10, I may employ the side portions or members thereof as 50 separate units, without cross bracing, by making them of sufficient strength in the first instance.

I may also utilize temporary current deflecting members in the form of sheet metal curtains 8, between the frames 10, where it is necessary in placing and setting the piles, each curtain having 55 side head and claw bars 21 to interlock with the before-mentioned laterally outstanding bars 22 of the frames.

As shown in Figure 6, each frame may be secured to its anchoring piles, and each such con-

nection may include a cap plate 28, bolted or welded to the upper end of the pile, and bolts 29, passing through thimbles 30, connecting the cap plate with the adjacent upper cross bar 18 of the frame. It will be apparent that this connection, like the other connections previously described, is such that the several parts, in removal of the structure, may be salvaged intact by mere reversal of the operations described in the installation of the structure, and in this way, among others, it is obvious the objects of my invention, first above stated, may be successfully carried out.

Having thus fully described my invention, what I claim is:

1. In a marine structure of the type described, spaced apart walls of interlocking sheet piling, cross frames spaced apart between said walls, and having means interlocking with the walls, means interlocking connecting and spacing said frames independently of the said walls, and means for anchoring each of said frames independently of said walls.

2. In a marine structure of the type described, spaced apart walls of interlocking sheet piling, cross frames between said walls, each having means to interlock with spaced points of the walls, each of said frames having pile guides, means interlocking connecting and spacing said frames at a plurality of points between, and independently of the said walls, and anchoring piles extending through said guides for securing the frames independently of said walls.

3. In a marine structure of the type described, spaced apart walls of interlocking sheet piling, a series of preformed spaced apart cross frames each having means at the ends thereof interlocking with said walls at a plurality of points of the latter, means for anchoring each of said frames between, and independently of, the walls, and interlocking means extending between and connecting said frames independently of the walls, said last named means also serving to properly space the frames apart and hold each thereof successively in position for anchoring.

4. In a marine structure of the type described, spaced apart walls of interlocking sheet piling arranged in outwardly convex arcuate sections, a series of spaced apart cross members extending transversely between said walls and having means at the ends thereof interlocking with the said walls at the junctures of said arcuate sections thereof, means interlocking with and extending between the cross members for spacing and connecting the same independently of the walls, and anchoring piles for securing said cross members arranged in line between the interlocked connections of the said members and said walls.

GEORGE H. ATKINSON.
